UNITED STATES PATENT OFFICE

2,505,913

HANGER FOR ANTEPENDIUM

John E. Rigali, Chicago, Ill., assignor to Deprato
Statuary Company, Chicago, Ill., a corporation
of Illinois

Application June 17, 1947, Serial No. 755,058

1 Claim. (Cl. 248—251)

1 This invention relates to improvements in a hanger for an antependium, and has for an object the provision of a hanger which is relatively simple and inexpensive in construction and which may readily be mounted on the underside of an altar table top.

Briefly, this invention comprises a channel member adapted to be secured in the recess provided in the underside of an altar table top. The inner end of a bracket is pivotally connected to the side walls of the channel member for movement from a collapsed position within the channel to an extended position at right angles to the channel member. The outer end of the bracket is formed with a hook portion to receive and support a curtain rod which, in turn, is adapted to support an antependium.

It is an important object of this invention to provide a bracket which may be pivoted into the enclosure formed by the channel-shaped member to conceal the bracket from view when same is not employed to support an antependium.

It is a further object of this invention to provide resilient means to yieldably resist pivotal movement of the hanger relative to the channel member, said hanger and said resilient means being formed and arranged to hold the hanger against accidental displacement from either its collapsed position or extended position.

This invention embodies other novel features, details of construction and arrangement of parts which are hereinafter set forth in the specification and claims, and illustrated in the accompanying drawing wherein:

Fig. 1 is a front elevational view illustrating a hanger for an antependium embodying features of this invention.

Fig. 2 is a transverse sectional view taken along the line 2—2 of Fig. 1, the bracket being shown in its extended position and supporting an antependium.

Fig. 3 is a detail plan view illustrating the hanger with the antependium rod removed.

Fig. 4 is a sectional view taken along the line 4—4 of Fig. 3.

Referring now to the drawing for a better understanding of this invention, the hanger comprises a channel member 6 formed with apertures 7 in its web 8. The channel member is adapted to be mounted in a recess 9 formed in the underside of an altar table top 11. A pair of screws 12 are inserted through the openings 7 for engagement in threaded openings provided in the altar table top. When the channel member 6 is mounted within its recess 9, the outer edges of

the side flanges 13 are adapted to be flush with the underside of the altar table top.

The inner end of a bracket 14 is journaled on a pivot pin 16 which is mounted at its ends in the flanges 13—13 of the channel member 6. The outer end of the bracket 14 is formed with a hook portion 17 to receive and support an antependium rod 18. The rod 18 is preferably formed with annular grooves 19 to receive the hook portion 17 to prevent axial displacement of the rod relative to the bracket 14.

The bracket 14 is adapted to be pivoted from its collapsed position, illustrated in dotted outline in Fig. 4, to its extended position, illustrated in Figs. 1, 2, 3 and 4. One end of a flat spring 21 is secured to the web 8 of the channel member 6 by means of a rivet 22, and the other end of the spring is disposed to yieldably resist movement of the bracket 14 from either its collapsed position or its extended position. It will be noted that the inner end of the bracket 14 is provided with a flat surface 23 to be engaged by the free end of the spring 21 to yieldably resist pivotal movement of the bracket from its extended position. An antependium 24 is provided with hooks 26 at spaced intervals along its upper edge for detachable engagement with the rod 18.

In the use of the hanger to support an antependium 24, the brackets 14 are pivoted from their collapsed positions to their extended positions, the brackets being held against accidental displacement from their extended positions by the engagement of the springs 21 against the flat surfaces 23 formed on the inner ends of the brackets. The rod 18 and antependium 24 are then mounted upon the hook portions 17 of the brackets 14, the hook portions 17 being disposed in the annular grooves 19 formed in the rod 18. When the rod 18 is thus mounted upon the hook portions of the brackets 14, it will be noted that the shoulders of the annular grooves 19 engage against the sides of the brackets 14 to prevent axial displacement of the rod 18 relative to the brackets. When the brackets 14 are not employed to support the antependium, they are moved to their collapsed position within their channel members 6 and are entirely concealed from view. While the channel members 6, brackets 14, and rod 18 may be formed of any suitable material, they are preferably formed of bronze to insure a long life of service.

While this invention has been shown in but one form, it is obvious to those skilled in the art that it is not so limited but is susceptible of various changes and modifications without departing

from the spirit and scope of the claimed invention.

I claim as my invention:

In a hanger for an antependium, a channel member of uniform transverse section, said channel member having side flanges and a connecting web, a bracket formed of flat material, one end of said bracket having a bearing aperture extending across the width thereof, a pivot pin mounted in said bearing aperture and having its ends connected to the side flanges of said channel member, said bracket having a recess extending inwardly from its side edge to form a hook portion on the free end of the bracket, said bracket being pivotally movable from a collapsed position between the side flanges of said channel member to an extended position at right angles to said channel member, a flat resilient spring secured at its one end to the web of said channel member, the free end of said flat resilient spring being dis-

posed to engage against and to yieldably resist pivotal movement of the bracket relative to said channel member, said bracket being formed at its pivot end with two flat surfaces disposed at right angles for alternate engagement by the free end of said flat resilient spring when the bracket is pivoted to its collapsed or extended positions.
